CLAIM

The ornamental design for a hair dryer, as shown and described.

DESCRIPTION

FIG. 1 is a perspective view of a hair dryer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a partially enlarged view showing the area "8" in FIG. 7.

The broken lines depict portions of the hair dryer in which the design is embodied that form no part of the claimed design.

The dot-dash broken lines indicating an enlargement portion of the design form no part of the claimed design.
